Patented July 2, 1912.

FIG. 2.

UNITED STATES PATENT OFFICE.

OMER L. HAYS, OF KIMBRO, SOUTH DAKOTA.

HAY-RACK.

1,031,068.

Specification of Letters Patent.

Patented July 2, 1912.

Application filed May 22, 1909. Serial No. 497,768.

To all whom it may concern:

Be it known that I, OMER L. HAYS, a citizen of the United States, residing at Kimbro, in the county of Stanley, State of South Dakota, have invented certain new and useful Improvements in Hay-Racks; and I do hereby declare the following to be a full, clear, and exact description of the invention, such as will enable others skilled in the art to which it appertains to make and use the same.

This invention relates to improvements in hay racks, of the knock-down type and has for its principal object to provide novel brackets for securing the sides and ends of the rack to the bottom of the rack, these brackets being so formed as to rigidly hold the sides and ends of the rack inclined outwardly from each other.

20 A further object of the invention is to provide a novel bracket consisting of two wedge-shaped integral socket members arranged at right angles relatively to each other, these brackets being designed to hold 25 the corner posts of adjacent sides and ends of the rack, so that these posts will be held as closely together as possible and locking of the posts together facilitated.

With the above objects in view the invention consists in certain novel details of construction and combination of parts hereinafter fully described and claimed, it being understood that various modifications may be made in the minor details of construction 35 within the scope of the appended claim.

In the accompanying drawing forming part of this specification:—Figure 1 is a side elevation of a hay rack embodying my improvements. Fig. 2 is an end elevation of 40 the hay rack. Fig. 3 is a detail perspective view of one of the corner brackets. Fig. 4 is a detail perspective view of one of the side socket members.

Referring now to the drawing in which 45 like characters of reference designate similar parts, 5 designates in general the rack bottom, this bottom being formed preferably of longitudinal spaced slats 6 which are connected together at their rear and front ends 50 by transverse slats 7. The bottom is supported upon bolsters 8 which support axle trees 9 that carry axles 10 which are equipped with wheels 11.

The sides of the rack are identical in construction and each comprises a plurality of longitudinal slats 12 connected intermediate

their ends by cross slats 13, and further connected together at their outer ends by posts 14; these posts inclining outwardly as clearly shown in Fig. 1. Inclined braces 15 are 60 connected at their lower ends to the posts and at their upper ends to the top slats of the sides and reinforce the sides against buckling.

The ends of the rack are identical and 65 each comprises spaced parallel slats 16, these slats being connected together intermediate their ends by transverse slats 17 and further having their outer ends connected together by outwardly inclining posts 18, these posts 70 being designed to bear upon the end posts 14 of the sides as clearly shown in Fig. 2.

The posts 14 of the sides and 18 of the ends will be hereinafter referred to as corner posts, and to secure these corner posts 75 to the corners of the bottom 5, novel brackets 19 are employed. These corner brackets are all identical in construction so that it will be necessary to minutely describe but one. Each corner bracket comprises a pair of 80 socket members 20, these socket members being integral with each other and being arranged at a right angle to each other. The inner walls 21 of the sockets are perpendicular to each other while the outer walls 22 of 85 the sockets incline outwardly from the inner walls of the sockets, so that each socket has approximately a wedge-shaped contour as may be clearly seen by reference to Fig. 3. The lower ends of the corner posts of adjacent sides and ends are beveled as shown at 90 24 to conform to the contour of these sockets, so that the posts are maintained at all times in intimate contact with each other.

In order to secure each corner bracket to 95 the bottom, an orificed strap 25 is secured to the inner wall 21 of one of the socket members, this strap being arranged adjacent to the inner upper corner of the socket member and being adapted to extend along the outer 100 edge of the adjacent longitudinal slat of the bottom to which the strap is bolted through the instrumentality of screws, bolts, or the like 26. An orificed strap 27 is arranged on the inner wall of the mating socket member 105 and is disposed adjacent to the lowermost inner corner of this socket member, this strap being designed to extend along the outer edge of a transverse end slat of the bottom and to be bolted thereto through the 110 instrumentality of screws, bolts or similar connectors 28.

- In order to secure the intermediate transverse slats 13 of the sides to the bottom, socket members 29 are employed, each socket member being provided on its inner wall with spaced approximately triangular shaped straps 30 which are designed to bear upon the overlapping ends of the transverse and outermost longitudinal slats of the bottom and to be secured thereto through the instrumentality of bolts 31 as shown in Fig. 4. The outer wall of each socket slopes outwardly and the lower end of the respective cross slat is tapered to conform to the contour of the socket.
- 15 For locking the corner slats in intimate contact with each other any desired lock may be employed, the lock here shown comprising U-shaped keepers 32 which receive the hooked extremities of substantially U-shaped hasps 33.

What is claimed, is:—

The combination with a hay rack including a bottom and sides and ends, said sides

and ends having contacting corner posts, of brackets secured to the corners of said bottom and engaging the lower ends of said corner posts, each of said brackets comprising a pair of integral socket members having their inner walls arranged at a right angle to each other for engaging a corner of said bottom, and having their outer walls inclining outwardly, the lower ends of said corner posts being mutilated to conform to the contour of said socket members whereby said posts are maintained in fixed relation relatively to each other, and locking means carried by said corner posts above said brackets for locking the sides and ends of said rack together.

In testimony whereof, I affix my signature, in presence of two witnesses.

OMER L. HAYS.

Witnesses:

W. F. HUDSON,
GLADDUS HALL.
